UNITED STATES PATENT OFFICE.

JOHN F. KRCMA, OF CHICAGO, ILLINOIS.

VENDING-MACHINE.

1,141,557.

Specification of Letters Patent.

Patented June 1, 1915.

Application filed November 27, 1911. Serial No. 662,673.

To all whom it may concern:

Be it known that I, JOHN F. KRCMA, a citizen of the United States, and a resident of the city of Chicago, county of Cook, and § State of Illinois, have invented certain new and useful Improvements in Vending-Machines; and I do hereby declare that the following is a full, clear, and exact description of the same, reference being had to the accompanying drawings, and to the numbers of reference marked thereon, which form a part of this specification.

This invention relates to improvements in coin operated vending machines, of that 15 class in which the operating or discharging mechanism is normally locked from movement, and in which the payment coin acts to release the same to operative position.

Vending machines as heretofore constructed, have usually consisted of many parts, so connected and combined as to render it difficult to keep the machine in order, and the frequent failures of such machines to operate tends to greatly lessen the patronage of the public and the consequent revenue 25 to be derived from such machines.

The object of this invention is to afford an exceedingly simple construction adapted to operate very positively, and so constructed 30 as to prevent effectually the discharge of more than one of the articles or packages sold.

The invention also has for its object an ejecting means whereby the vended article 35 is mechanically and positively discharged from the machine, simultaneously positioning another of said articles preparatory to discharge.

It is also an object of the invention to afford an improved locking mechanism, whereby operation of the machine cannot be effected except through coöperation with a coin of the proper denomination.

It is a further object of the invention to afford a construction in which unauthorized interference with the machine is prevented, and in which a plurality of compartments for the articles to be dispensed are provided, from which said articles are dispensed successively.

It is, of course, an object of the invention to greatly simplify, strengthen and increase durability and reliability of the machine.

A preferred form of the invention is hereinafter more fully described.

In the drawings: Figure 1 is a view in front elevation of a machine embodying my invention. Fig. 2 is a section taken through the case only on line 2—2 of Fig. 1, and showing the mechanism in side elevation. Fig. 3 is a section taken through the case on line 3—3 of Fig. 2, and showing the mechanism in rear elevation. Fig. 4 is a central section on line 4—4 of Fig. 3. Fig. 5 is a section on line 5—5 of Fig. 4. Fig. 6 is a section on line 6—6 of Fig. 4. Fig. 7 is an enlarged fragmentary vertical section of the front plate, and a face view of the coin operated mechanism attached thereto. Fig. 8 is an enlarged rear elevation thereof. Fig. 9 is an enlarged fragmentary sectional detail illustrating the release of the locking mechanism by the coin. Fig. 10 is a fragmentary section taken on line 10—10 of Fig. 3, with parts omitted.

As shown in the drawings: The mechanism is contained within a case constructed of any suitable material and comprising a bottom 1, a top 2, side walls 3, and a removable front plate 4, the latter of which is conveniently of cast or stamped metal and is provided in its upper part with an enlarged opening therethrough, in which is set a glass plate 5, permitting a view of the interior commodity compartments to be plainly seen by the would-be purchaser.

Mounted upon the base or bottom of the case is a suitable base frame 6, having legs 7 and 8, affording a support and engagement therefor in the bottom of the case. Journaled transversely the machine on the end members of said frame, is a cam shaft 9, having as many throws thereon as there are vertical compartments for the commodities to be dispensed (in the construction shown in the drawings, there are four). Said frame, as shown, affords at its top a succession of slide recesses extending from front to rear thereof, and slidably engaged in each is a flat cam plate 10, the rear end of which is provided with an enlarged head 11, which is inserted through a suitable slot in a levered striking plate 12, secured integrally to the upper end of which is a rearwardly directed plate 13.

The lower end of the levered striking plate extends through suitable slots in said frame shown in Fig. 6, and said levered striking plates extend upwardly through an upper frame or table 14, supported on, and secured to the frame 6, and provided with rear-

wardly opening slots, one for the head of each of said levered striking plates, as shown in Fig. 5.

As shown, a shoulder 14^a is provided at the upper end on each levered striking plate, and at each side thereof, which slides on said table at each side the slot to hold said plate in operative position, and a strong pulling spring 15, is secured at the end of the plate 13, and extends forwardly through a slot or opening in the levered striking plate 12, and is engaged to said table 14, to exert tension at all times thereon, acting to draw the same forwardly when released.

Each of the sliding cam plates is provided with an upstanding finger 16, thereon, and the throws or projections on said shaft for actuating the levered striking plate rearwardly are arranged to successively engage said fingers in actuating the machine, that is to say, there being four compartments and four levered striking plates for the machine to be actuated, the four throws or projections α , α^1 , α^2 and α^3 , on the shaft are arranged at ninety degrees apart thereon.

Rigidly secured at its rear end on the table or frame before described, is an upright casing affording four vertical compartments, the front wall of which is afforded by the glass in the front wall of the machine, and the bottom of which is afforded by the plates 13, integrally connected with the levered striking plates, as shown in Fig. 4, or by the table when the same are retracted, and, as shown, relatively weak spring detents 17, are provided in front of each of said compartments and act to prevent ejection of the article to be vended therefrom until positively impelled by the striking plate as the machine is actuated.

Secured on one end of the shaft 9 is a ratchet wheel 18, having four teeth or ratchets thereon arranged ninety degrees apart, or to correspond with the number of throws on said shaft (whatsoever the number) and the number of compartments for the articles to be vended. Said teeth are directed rearwardly.

Pivotedly engaged on said frame 6, as shown in Figs. 2 and 6, is a pawl 19, having a notched or ratcheted head adapted to engage the teeth of the ratchet wheel 18, to hold the same from movement after each actuation thereof. As shown, a pulling spring 20, is secured to said detent and to a suitable part of the frame and acts to hold said pawl at all times in engagement with the ratchet wheel.

Said front plate 4, at a point sufficiently above the table to permit the ready discharge of the articles to be vended, extends outwardly and downwardly, as indicated at 21, and is cut away at the bottom to permit the articles vended, to be withdrawn from beneath the same, and secured to and ex-

tending upwardly substantially in the plane of the upper portion of the front frame plate, is a plate 22, which extends to a sufficient height to prevent unauthorized interference or manipulation with the mechanism 70 of the machine by the insertion of any instrument upwardly into the machine. Said front plate is provided near the side thereof, corresponding with the position of said ratchet wheel 18, with a coin slot 23, and, as 75 shown, with an elongated slot below the same through which protrudes the lever 24, for actuating the machine. Slidably supported on the inner face of said front plate 4, is a slide bar 25, with which the lever 24, 80 is rigidly connected and which is provided on its inner side with ratchet teeth 26, adapted to be engaged by a pawl 27, pivotally supported on said frame and controlled by a spring 28, at all times to hold said pawl in 85 position to engage said ratchet bar at any position in the movement of the slide bar, whether upwardly or downwardly, less than the full limit of travel thereof. Integrally secured on said slide bar on the outer and 90 inner side thereof respectively, are outstanding lugs 30 and 31. Pivotally engaged near its upper end at 32' on the inner side of the lug 30, is a lever 32, flanged inwardly to afford a part of the coin chute, and at its 95 lower or free end provided with an outwardly directed finger or detent 33, adapted to engage in the teeth or ratchets 34 and 35, on the inner side of the front plate, and a pulling spring 36, is engaged at the lower 100 end of said lever 32, and at its upper end is engaged on said lug 30, and acts to hold the said levered chute section normally elevated with the detent 33, thereon in position to engage the ratchet tooth or shoulder 35, should 105 an attempt be made to actuate the slide bar without the insertion of a coin. As shown, a coin groove is provided in the inner face of said front plate beneath said lever 32, and said lever at its lower end is provided with 110 an inwardly directed flange or plate 37, positioned to be engaged by a falling coin 38, of the proper denomination to swing the lower end of the lever outwardly only sufficient to pass said tooth 35, as shown in Fig. 9, permitting the machine to operate. Any smaller coin, of course, falls to the bottom of the machine without operating the same. Positioned directly above said lever 32, which affords a movable section of the coin 115 chute, is the stationary coin chute comprising rearwardly directed parallel side walls or plates 39 and 40, of brass or other non-magnetic metal, spaced a distance apart to permit a coin inserted in the coin slot, to 120 fall downwardly therebetween and into the channel afforded between the front plate and the movable or levered coin chute section 32. As shown, a small permanent magnet 41, is secured in an inclined position, as 125

130

shown in Figs. 2 and 7, in position to be contacted by a slug of any magnetic material inserted in the coin slot, and acting to swing such slug out of its normal path sufficiently to permit the same to drop within the box without releasing the detent 33.

Pivotedly supported upon the lug 31, is a push rod or pivoted lever 42, which extends into position to engage the successive 10 ratchet teeth therebeneath to rotate said ratchet wheel and consequently the cam shaft, with each full actuation of the slide bar 25.

As shown, a strong pulling spring 43, is 15 engaged at the upper end thereof and to any convenient point on the front plate or one of the walls, for example 39, of the stationary coin chute, and acts by its tension to hold said push bar at all times in position to 20 engage the ratchet teeth beneath the same, but permits the same to swing sufficiently with the rotation of said ratchet wheel to insure full actuation or rotation for ninety degrees of the cam shaft.

25 The inner face of the front plate 4 opposite the flange 37 or lever 32 is recessed angularly at 45 in such manner that the vertical face of said recess lies substantially parallel with the face of said flange 37, so 30 that upon the introduction of a coin or token of the proper size therebetween and a downward movement of the slide bar 25 carrying said lever 32, said coin will roll on said angular wall of recess 45, and thus will force 35 out said lever 32 on its pivot 32', for a purpose hereinafter to be described. By reference to Fig. 9 it will be observed that the lower projecting end of said recess 45 normally forms a stop for the coin 38 so that 40 the latter will be retained until it is rolled past said end by the downward movement of the slide bar 25.

The operation is as follows: The magazines or vertical compartments are filled 45 with the commodities to be vended, for example, matches in boxes or other suitable receptacles or containers, which are stacked one upon another to fill the respective compartments and resting upon the table or 50 upon the plates 13, integrally secured at the top of each of the levered striking plates 12. If now a coin be inserted in the coin slot, it falls therefrom past the magnet, which is positioned to engage any slug of magnetic 55 material and divert the same from the chute. The coin, however, falls from the stationery chute into the levered chute section and into a pocket formed by the flange 37 on the lever and the recess 45 on the 60 frame or front plate, as shown in Fig. 9, and with the first preliminary downward movement of the lever 24, for actuating the machine, the coin rolls downwardly on the inclined wall of said pocket, and if the coin 65 be of the proper denomination forces in-

wardly the lever 32 and with it the detent 33, on the end thereof sufficiently to permit the same to pass the tooth 35, thereby permitting free downward movement of the slide bar to the full limit of its travel. The 70 coin now falls from the chute and into any suitable receptacle therefor and at about the moment that the coin is discharged, the push bar 42, which engaged the forward upper tooth on the ratchet wheel at the beginning of the downward movement of the slide bar, completes the rotation of the ratchet wheel for ninety degrees or sufficient to release the previously retracted levered 75 striking plate by the rotation of the cam shaft, and permitting said striking plate to be projected violently forward under the impulse of its spring, thus striking the package, box or receptacle of the article to be vended, from the table and into the discharge space in front of the machine, from 80 which it may be removed by the purchaser. Of course, the rotation of the ratchet wheel and consequent rotation of the cam shaft, retracts a succeeding striking plate preparatory 85 to the next delivery of an article from the machine with the delivery of the next coin thereinto, and in this manner the articles are delivered successively from the various receptacles therefor until the entire 90 contents of the machine have been discharged as purchased. Should the purchaser attempt to secure more than one article for a single coin, the machine immediately locks with the slightest reverse 95 movement of the slide bar, the detent or pawl 27, engaging the ratchet tooth on the slide bar and acting to prevent the return movement thereof until the completion of the full travel and consequent release of one 100 striking plate. Should a coin of smaller size or a slug be inserted, even though but very slightly smaller than the required coin, the machine locks by engagement of the finger 33, against the tooth 35, the coin 110 or slug dropping to the bottom of the box when the actuating lever is released.

Of course, numerous details and modifications in the construction and operation may be varied, but I have shown and described 115 but one (and that the preferred) form of my construction, and I therefore do not purpose limiting myself otherwise than necessitated by the prior art.

I claim as my invention:—

1. In a device of the class described, a frame recessed angularly, a slidable bar thereon, a lever pivoted on said bar and adapted, together with said frame, to form a coin slot, said recess acting normally to 125 check the passage of a coin, means for actuating said sliding bar causing the coin to roll in said angular recess and thrust said pivoted lever outwardly to permit passage of the coin, and means on said lever adapted 130

to engage said frame to prevent actuation of said sliding bar without the coaction of a proper coin.

2. In a device of the class described, a frame recessed angularly, a slideable bar thereon, a lever pivoted on said bar and adapted, together with said frame, to form a coin slot, said recess acting normally to check the passage of a coin, a flange on said lever forming a part of said slot, means for actuating said slideable bar causing the coin to roll in said angular recess and thrust said pivoted lever outwardly to permit passage of the coin, a spring to hold said lever normally toward said frame, and a tooth on said lever adapted to engage a notch in said frame to prevent actuation of said slideable bar without the coaction of a proper coin.
3. In a device of the class described, an angularly recessed frame, a slideable bar

thereon, a lever pivoted on said bar adapted to form one side of a coin slot, a flange on said lever, said recess in said frame coacting with said flange to check the passage of a coin in said slot, means for actuating said slideable bar causing the coin to roll in said recess and thrust said pivoted lever outwardly to permit passage of the coin, and a tooth on said flanged lever adapted to engage a notch in said frame to prevent actuation of said slideable bar without the coaction of a proper coin.

In testimony whereof I have hereunto subscribed my name in the presence of two subscribing witnesses.

JOHN F. KRCMA.
